Primary Examiner — Kevin Rudzinski*Assistant Examiner* — Sean D Lough(74) *Attorney, Agent, or Firm* — Marshall, Gerstein & Borun LLP(57) **CLAIM**

The ornamental design for a driver housing, as shown and described.

DESCRIPTION

FIG. 1 is a perspective view showing a new design for a driver housing;

FIG. 2 is a front view of the driver housing of FIG. 1;

FIG. 3 is a rear view of the driver housing of FIG. 1;

FIG. 4 is a left-side view of the driver housing of FIG. 1;

FIG. 5 is a right-side view of the driver housing of FIG. 1;

FIG. 6 is a top view of the driver housing of FIG. 1; and,

FIG. 7 is a bottom view of the driver housing of FIG. 1.

The dashed lines showing portions of the driver housing are included for the purpose of illustrating environment and form no part of the claimed design.

1 Claim, 5 Drawing Sheets(56)
